UNITED STATES PATENT OFFICE

146,648

DESIGN FOR A DISPENSING UNIT FOR AN OIL BAR

Erling G. Fossum, Chicago, Ill., assignor to
Stewart-Warner Corporation, Chicago, Ill., a
corporation of Virginia

Application March 9, 1946, Serial No. 127,277

Term of patent 14 years

(Cl. D52—2)

To all whom it may concern:

Be it known that I, Erling G. Fossum, a citizen of the United States, residing at Chicago, in the county of Cook and State of Illinois, have invented a new, original, and ornamental Design for Dispensing Unit for an Oil Bar, of which the following is a specification, reference being had to the accompanying drawing, forming part thereof.

The figure is a perspective view of a dispensing unit for an oil bar, showing my new design.

The back of the dispensing unit for an oil bar is plain, and the left side is similar in appearance to the right side.

I claim:

The ornamental design for a dispensing unit for an oil bar, substantially as shown and described.

ERLING G. FOSSUM.
